ABSTRACT OF THE DISCLOSURE

A direct current (VLF) switch using silicon controlled rectifiers at their power frequency rating. SCR's selectively short-out turns in an antenna tuning coil to bring about a change in inductance. A turn-on signal is required to close the SCR switch, a turn-off signal to open the SCR switch and a bias supply to maintain the SCR switch in a closed state.

BACKGROUND OF THE INVENTION

The present invention relates generally to switching circuits and more particularly to switching circuits employing SCR's to selectively tune resonant circuits.

The Navy has the communications requirement of keeping in contact with ships and submarines at sea, at great distances up to several thousands of miles. Reception must be possible 24 hours a day. To achieve this communication to fleets and task forces with the greatest reliability, high power, low frequency (LF) and very low frequency (VLF) transmitters are used. Transmitters which use up to 1 megawatt of power at frequencies of from 15 kHz. to 30 kHz. are strategically located around the world. The transmitting antennas used on the above transmitters, being electrically short in physical size, inherently have a very high "Q." This seriously limits the (CW) keying speed and when frequency shift keying is used, the transmitters suffer because of the severe distortions produced by the limited bandwidth of the antenna resonant circuit.

The problem of adapting high-speed communications to high power (VLF) transmitters can be solved by having the resonant antenna circuits tuned at all times synchronously with the instantaneous driving frequency. Heretofore, this has been attempted by the use of large saturable reactors which change their reactance to compensate for the change in frequency by means of a D.-C. control voltage. These reactors are slow in action, inefficient, large in size, very costly, and need relatively large amounts of D.-C. power. The saturable reactor works on the principle of varying the D.-C. reactor control current in accordance with the teletype input signal. The (RF) winding of the reactor is connected in parallel with part of the antenna loading coils. As the D.-C. varies, so does the inductance of the reactor, which in turn, changes the resonant frequency of the antenna at the teletype keying rate. The transmitter output frequency is synchronized with the changes of the antenna since the keying voltage is obtained from the reactor control circuit. The voltage developed across a low value resistor (0.04 ohm, for example) in series with the reactor control circuit is fed back to the oscillator.

With the use of SCR's to modulate the antenna tuner, switching speeds are almost instantaneous, i.e., in microseconds; efficiency is considerably higher; they can be easily packaged in smaller units; are relatively inexpensive; and do not require great amounts of D.-C. power.

When SCR's are used to control or switch signals at frequencies much above conventional power frequencies,

2

they must be derated because of limits on di/dt imposed by turn-on phenomena. For example, an SCR is characterized by turn-on over a relatively small fraction of the total junction upon gating. Spreading of the "on" area to the total available "on" area requires up to 40 or 50 microseconds for high current SCR's. As a result, when such SCR's are used to switch signals of 30 kHz. or therabouts (33 microsecond period) the complete junction is never used and advantage cannot be taken of the full device rating.

SUMMARY

The general purpose of this invention is to provide a circuit configuration for employing SCR's at their power frequency ratings to control signals at very low frequencies (up through 30 kHz.). Diodes are added in series with each of the SCR's, thus providing a circuit which lends itself to D.-C. biasing of the SCR's without changing the external circuit. D.-C. current is caused to flow through the SCR's from an external low voltage D.-C. source to keep the SCR's on when once turned on. To turn the switch off, the D.-C. bias source is simply opened. Once the SCR's are turned on and the bias loop closed, the SCR's can be maintained fully on by the bias along independently of external circuit conditions.

An object of the present invention is to provide a new and improved bistable switch.

Another object of the invention is to provide a new and improved bistable switch employing D.-C. biased silicon-controlled rectifiers.

Still another object of the invention is to provide a new and improved bistable switch that is capable of switching at high speed and which utilizes a minimum number of components.

A further object of the invention is to employ SCR's at their power frequency ratings to control signals at (VLF) frequencies.

A still further object is to provide switching circuits employing SCR's to selectively tune resonant circuits.

Still another object of the invention is to provide switching circuits employing SCR's to modulate an antenna tuning circuit by sequentially shorting or opening coils.

BRIEF DESCRIPTION OF THE DRAWINGS

With these and other objects in view, as will herein-after more fully appear, and which will be more particularly pointed out in the appended claims, reference is now made to the following description taken in connection with the accompanying drawings in which:

FIG. 1 is a schematic diagram of a prior art device and FIG. 2 is a graphical representation useful in understanding the prior art.

FIG. 3 is a schematic diagram of a switching circuit, and FIG. 4 is a graphical representation useful in understanding one embodiment of the present invention.

FIG. 5 is a schematic diagram of a switching circuit including a triggering circuit, and FIG. 6 is a graphical representation useful in understanding one embodiment of the invention.

FIG. 7 is a schematic diagram of a preferred embodiment of the present invention.

INTRODUCTION

(VLF) antennas, although very large physically, are very short electrically. They display an input impedance which is highly capacitive. In practice, the antenna capacitance is tuned out with a large coil, and as a result of this combination, the transmitter sees a very high "Q"-series resonant circuit as a load. The "Q" is sufficiently high that even the 40 or 50-cycle shift in transmitter frequency employed in frequency shift key-

ing techniques results in a serious change in antenna system impedance. To overcome this difficulty, circuits have been developed for shifting the tuning of the antenna with shifts in transmitter frequency by changing the inductance of the tuning coil.

The requirements imposed by the antenna tuner on the switch are severe for SCR's. SCR ratings were considered in the light of the prior art circuit configuration shown in FIG. 1. The technique employed is to control the inductance of a large coil 11, used to tune the antenna by shorting out turns of the coil 11 with electrically controllable switches depicted as silicon controlled rectifiers SCR 12 and SCR 13.

In this explanation, the term "current" is used to describe an energy flow from a first plane of potential toward a second plane of potential, where the first plane is of a polarity positive with respect to that of the second plane. In that the operation of a silicon controlled rectifier is much like a latching switch, the terms "conducting" and "nonconducting," "open" and "closed," or "on" and "off" are used to describe the states or conditions of these switches in the following explanation.

As shown in FIG. 1, the SCR's 12 and 13 are gated on alternate half cycles, conduct for a half cycle and then turn off for a half cycle. FIG. 2 is a graphical representation of the current flow in the circuit of FIG. 1. In such use at 30 kc., each SCR is gated and only partially turns on in the 16 microseconds that it conducts before voltage is reversed on it and it turns off. In such use, only a portion of junction is used and the SCR must be derated accordingly. In addition, further derating is required because of the effects of passing through the highly dissipative initial turn-on period 30,000 times per second. For example, a 110 amp. r.m.s. SCR must be derated to about 25 amp r.m.s. for such use.

The present invention provides a circuit configuration for utilizing SCR's at their power frequency ratings to control signals at very low frequencies. Any attempt to reduce the number of switch sections required by using the highest voltage, highest current SCR's available was restricted considerably by dv/dt and recovery time characteristics of the SCR's. At 30 kc., the dv/dt which the switch must support is $(0.19 \times v_{pk})$ volts/microsecond in the steady state, or about twice this in the transient state. A realistic dv/dt rating is 100 volts/microsecond when turn-on and recovery time requirements are considered. SCR's with higher dv/dt ratings are available; however, some sacrifice in other ratings must be made. This imposes a peak voltage limit on the SCR of about $100/0.38=270$ volts. On this basis, it was decided that without using SCR's in series, the voltage rating of the switch should not exceed 200 volts r.m.s. Considering the double voltage transient, SCR's rated at 600 volts must be employed ($200 \times \sqrt{2} \times 2=566$ volts).

The use of high current SCR's is hampered by recovery time. One method of meeting the recovery times required by 30 kc. operation is to use an SCR selected for this purpose. One of the device characteristics which accompanies fast recovery appears to be high forward voltage drop during conduction, which means lower current rating because of junction heating. It was concluded that the SCR to be used would be a 600-volt device with a power frequency r.m.s. current rating in the range of 55 to 110 amps. In a directly operated switch configuration, the switch rating for a pair of SCR's would be about 8 kva. With some means of keeping the SCR's on during their nonconducting half cycle, this switch can be increased to 20 kva.

DESCRIPTION OF THE PREFERRED EMBODIMENT

From inspection of FIG. 3, it is apparent that an (RF) switch circuit in accordance with the invention in effect comprises three subcircuits. Input conductor 27 is coupled to a diode 19 at the cathode 19c. The diode 19

has an anode 19a coupled through conductor 28 to the cathode 17c of SCR 17. Anode 17a of SCR 17 is connected to input terminal 16 through conductor 26. Current flow in this first subcircuit is designated as I_A in FIGS. 3 and 4.

Input conductor 27 is also connected to anode 21a of diode 21. Cathode 21c of diode 21 is connected through conductor 24 to anode 18a of SCR 18. Cathode 18c of SCR 18 is connected to input terminal 16 through conductor 26. Current flow in this second subcircuit is designated I_A' in FIGS. 3 and 4.

The bias circuit I_B begins with an outside voltage source 22 having a positive terminal connected to one end of current limiting resistor 23 which has its other end connected to fixed contact of a so-called mechanical make and break switch 14. The other fixed contact of a switch 14 is connected to cathode 21c of a diode 21 and to anode 18a of an SCR 18 through conductor 24. Cathode 18c of SCR 18 is connected to terminal 16 and to anode 17a of SCR 17 through conductor 26. Cathode 17c of SCR 17 is connected to the negative side of an outside voltage source 22 and to the anode 19a of diode 19. Bias current flow in this third subcircuit is designated I_B in FIGS. 3 and 4.

Operation of an embodiment of the RF switch circuit of the invention as shown in FIG. 3 is as follows. With the switch 14 closed before the SCR's 17 and 18 are gated, the voltage across SCR's 17 and 18 is the external terminal voltage across terminals 15 and 16 shared with the diodes 19 and 21 plus a portion of the bias voltage E. When SCR's 17 and 18 are triggered "on," either simultaneously or synchronously with the external bias voltage, SCR's 17 and 18 turn "on" or enter a conduction state and are kept there by current flowing from the bias source 22 through a current limiting resistor 23. "On" data pulses, a series of square waves synchronous with the antenna current, are obtained from an "on" driver (not shown) and fed to gates 17g and 18g of SCR's 17 and 18. Once the SCR's 17 and 18 are triggered "on" and bias current I_B begins to flow, the SCR's 17 and 18 remain "on" regardless of the voltage on the external terminals 15 and 16.

The diodes 19 and 21 in the circuit support any internal back voltages which would act to turn the SCR's 17 and 18 "off." D.-C. bias current I_B flows in and is confined by the diodes 19 and 21 to the subcircuit loop as indicated by I_B . External circuit current flows in first subcircuit path I_A or in second subcircuit path I_A' depending upon the polarity of an external signal.

To turn the (RF) switch circuit "off," bias current I_B is interrupted by opening switch 14. Because of opposite polarities of the external signal, external circuit current flow can flow through only one SCR at any time. If at the time of opening switch 14, external current is flowing in path I_A , SCR 18 will turn "off," leaving SCR 17 conducting. When the external current returns to zero SCR 17 will turn "off." Since SCR 18 is already "off," current cannot reverse. After a few microseconds to allow the SCR's 17 and 18 to fully recover, switch 14 may be closed to arm the (RF) switch circuit for "turn on" by triggering when required.

An alternative embodiment to closing switch 14 is shown in FIG. 5 where a resonant crowbar arrangement may be employed on the bias source 22'. With the (RF) switch circuit of the invention "on" and the bias source 22' supplying bias current I_B as shown in FIG. 6, "turn off" is initiated by triggering the crowbar SCR 29 by applying a trigger pulse to gate 29g. The power supply capacitor 31 is discharged through inductance 32 in a resonant manner such that it swings negative. This negative swing turns off crowbar SCR 29. Filter choke 33 is of relatively high inductance and keeps current from the bias source 22' from increasing rapidly. As a result, the negative voltage remains at the terminals of capacitor 31 until capacitor 31 can be restored to its normal level

"E" by current flow I_{DC} through inductance 33 and through resistor 23' by way of the diode 21' in the (RF) switch.

Since the voltage has gone negative, the SCR's 17' and 18' are back biased and turned "off." Since the SCR's will naturally turn "off" when the current through them goes to zero, it is only necessary to remove the bias momentarily until one of the pair turns "off." The above crowbar "turn off" system operates by removing the bias for an interval in excess of one-half the period of the (RF) cycle representing the lowest operating frequency. In one embodiment utilizing the circuit of this invention, "turn off" occurred at the first (RF) zero crossing that followed an "off" trigger. This "off" trigger was originally initiated by a negative going, trailing edge of a data pulse square wave applied to gate 29g of SCR 29.

The (RF) switch circuit of the invention may be broken into three subsections: the switch section itself; drivers; and bias. In the switch section, D.-C. current is caused to flow through the SCR's 17 and 18 from an external low voltage D.-C. source 22 to keep SCR's 17 and 18 on when once turned on. To turn the switch off, the D.-C. bias source is simply opened. A circuit diagram of a complete switch assembly, with bias, in accordance with the invention as used on a (VLF) antenna tuner, is shown in FIG. 7.

Bias supply involves basically an effective means of bias control. When the (RF) switch circuit is driven "on" by gate drive, bias current flows and keeps the switch on. In order to turn the switch circuit "off" a resonant crowbar circuit is used. This circuit when triggered places a low inductance across the output capacitance of the power supply. The resulting resonant discharge of the capacitor causes the effective bias voltage to reverse and stop the bias current through the SCR's 17' and 18' for a time sufficient for them to recover by forced commutation from the (VLF) signal. Recovery of the power supply then reapplies bias voltage to the switch in preparation for the next turn on signal. Functioning of the bias control is illustrated in FIGS. 5 and 6.

Use of a bias system as described above requires some form of "turn-off" drive as well as a "turn-on" drive. "Turn-on" of the switch SCR's 17' and 18' is accomplished with a burst of gate pulses timed to occur with current zeroes in the antenna current. A burst is used as insurance of "turn-on" in view of certain dynamic conditions which may occur in the system as a result of multiple switch operations simultaneously. "Turn-off" is accomplished by a single pulse applied to the gate 29' of crowbar SCR 29'.

The energy for removing the bias is derived from capacitor 31', which is charged to essentially the same voltage as the bias source 22' by sampling the voltage drop across resistor 23" during the time the (RC) switch circuit is conducting. Since the capacitor voltage is of the opposite polarity to that of the bias source 22', whenever the crowbar SCR 29' conducts, the bias to the (RF) switch is removed by cancellation.

The coupling of a switching coil 35 to a helix (not shown) is preset, to the amount of reactance change required, as the transmitter keyer shifts the frequency. As the angle of the switching coil 35 to the horizontal decreases, coupling increases and, not only frequency shift (change of resistance) increases, but, so does the (kva) across the switching coil 35 and the SCR's. The additional circuit components not already discussed are for transient suppression and for rounding off sharp voltage edges which might cause retriggering of the SCR's by dv/dt and lead to "turn-off" problems.

To assist those skilled in the art in making and using a preferred embodiment of the invention, typical circuit values for the embodiment illustrated in FIG. 7 are set forth below. It will be understood, however, that such typical values are given by way of illustration only and in no sense by way of limitation. In general, stock com-

ponents were utilized, and the circuit can be made physically smaller and more economical as specially sized or designed components are utilized.

5	SCR's 17" and 18"	W254M.
	SCR 29'	C20D
	Diodes 19" and 21"	IN1190A.
	Diodes 38 and 42	IN1348A
	Resistor 23"	5 ohms.
10	Resistor 36	75 ohms.
	Resistor 41	5 K ohms.
	Capacitor 31'	8 μ F.
	Capacitor 37	.01 μ F.
	Capacitor 39	.47 μ F.
15	Inductance 32'	10 μ H.
	Inductance 33'	1 μ H.

Thus a switching circuit utilizing SCR's to modulate an antenna tuning circuit by sequentially shorting or opening coils has been disclosed. The present invention utilizes a minimum number of components and employs SCR's at their power frequency ratings to control signals at (VLF) frequencies.

It should be understood, of course, that the foregoing disclosure relates to only preferred embodiments of the invention and that numerous modifications or alterations may be made therein without departing from the spirit and the scope of the invention as set forth in the appended claims.

What is claimed is:

1. A circuit for controlling current flow through a load comprising:
first and second solid state controlled rectifiers each having an anode, a cathode and a gate control element, the anode of said first controlled rectifier and the cathode of said second controlled rectifier being connected to a first end of said load;
first and second diodes, each having an anode and a cathode, the cathode of said first diode and the anode of said second diode being connected to a second end of said load; and
control means connected at a first end to a junction of the cathode of said first controlled rectifier and the anode of said first diode and connected at a second end to a junction of the anode of said second controlled rectifier and the cathode of said second diode, whereby D.-C. biasing is provided for maintaining conduction and an "off" signal for discontinuing conduction of said solid state controlled rectifiers.
2. The circuit of claim 1 wherein said control means comprises:
an external voltage source for providing a bias voltage; a current limiting means connected to said voltage source for limiting the flow of bias current; and switch means connected in series with said external voltage source and said current limiting means and adapted for switching said solid state controlled rectifiers from their conducting to their nonconducting state.
3. The circuit of claim 2 wherein said switch means comprises:
a mechanical make and break switch.
4. The circuit of claim 3 wherein said switch means comprises:
a resonant crowbar "turn-off" circuit having a solid state controlled rectifier, gated by an external data pulse for removing the bias current and thereby switching said circuit to a nonconducting state.
5. A switching circuit for controlling current flow from an alternating current source through a load comprising:
a first subcircuit having a first electron discharge means and a first diode in series with each other and in series with said load and operating in a first polarity with respect to an incoming signal;
a second subcircuit having a second electron discharge means and a second diode in series with each other

and in series with said load and in parallel relationship with said first subcircuit and operating in a second polarity with respect to an incoming signal; and
 a third subcircuit having said first and second electron discharge means in series relationship with each other and in series relationship with an external bias source and a switch means, said third subcircuit thereby providing D.-C. biasing for maintaining conduction and an "off" signal for discontinuing conduction of said first and second subcircuits. 10

6. The circuit of claim 5 wherein said first and second electron discharge means are silicon controlled rectifiers. 5

7. A circuit for controlling current flow through a load comprising: 15

first and second silicon controlled rectifiers each having an anode, a cathode and a gate control element, the anode of said first controlled rectifier and the cathode of said second controlled rectifier being connected to a first end of said load;

first and second diodes, each having an anode and a cathode, the cathode of said first diode and the anode of said second diode being connected to a second end of said load; 20

20 DONALD D. FORRER, Primary Examiner
 J. D. FREN, Assistant Examiner

25 307—305

an external voltage source adapted to provide a bias current for said circuit; current limiting means connected to said voltage source for limiting the flow of bias current; a resonant crowbar "turn-off" circuit having a silicon controlled rectifier and gated by an external data pulse, said "turn-off" circuit adapted for removing the bias current and thereby switching said circuit to a nonconducting state; and reactance means for providing transient suppression and for rounding off sharp voltage edges thereby preventing undesirable retriggering of said silicon controlled rectifiers.
